Application August 10, 1944, Serial No. 548,909

21 Claims. (Cl. 235—59)

1

This invention relates to new and useful improvements in computing and recording machines, and has particular reference to improvements in the totalizers used thereon.

A main object of the invention is to provide simple and efficient means in the totalizer itself which, under the control of the numeral wheels thereof, will be able to actuate and control mechanical or electrical devices outside the totalizer to effect any desired operations.

Another object is to provide an improved structure in which the parts employed are fewer, simpler in operation, more economical to manufacture and more reliable in effecting desired results in every day operation.

A more specific object is to provide an improved add-1 mechanism which is substantially built into the totalizer itself.

Further and more specific objects, features, and advantages will more clearly appear from the proper consideration of the annexed drawings which form part of the following specification and which illustrate a present preferred form which the invention may assume.

The totalizer employed is generally of the type shown in U. S. Patent No. 1,270,471, issued June 25, 1918, to J. C. Wahl and entitled "Calculating machine." Other features are novel improvements over the clear signal mechanism shown in U. S. Patent No. 2,083,994, issued June 15, 1937, to F. A. Hart, and entitled "Accounting machine."

Briefly and generally, the invention concerns a computing and printing machine, preferably of the "Remington" type in which there is a frame, a to-and-fro travelling carriage and a totalizer mounted on the carriage and receiving entries as it passes a point on the machine where it becomes associated with the usual actuator mechanism for the addition to or subtraction of amounts from the totalizer.

According to the invention the totalizer has a plurality of wheels set to represent numerical values entered therein and also a plurality of fingers projecting therefrom with means associated with the wheels and connected to the respective fingers to move the fingers from one position to another as the respective wheels move from one position to another position.

More particularly the fingers are moved especially when the wheels move to and from their respective zero positions. When adapted to be used as a device to control the add-1 operation in machines of this type the fingers are associated with a fixed plate on the frame and, when in one position, contact with said plate as the carriage

2

is moved past said plate. When in another position the fingers do not make contact with the plate. The wheels of the totalizer are provided with means whereby when they are in their zero position, the connecting mechanism to the fingers will move the fingers to a position where they will not contact the plate. On the other hand when the wheels are in any position except the zero position, the fingers are disposed so that they do not contact the plate. Preferably, in one adaptation of the device the fingers in contacting the plate keep closed a circuit in which is a relay. When all the fingers are out of contact with the plate this circuit is broken and the relay deenergized to effect a circuit contact closure which, for example, may set circuit arrangements to print a tens complement in writing a total. Of course it is clear that this arrangement of parts can be employed to accomplish many other new and useful results than the particular one set forth here and hereinafter.

Still more particularly it is also provided with means whereby when all the fingers are in a predetermined position a clear signal element is permitted to move to a position whereby a clear signal or symbol can be printed at the proper time.

Means are also provided whereby, when the actuator is about to enter items into the totalizer, and the wheels thereof must be moved, the connection between the wheels and the finger operating means is temporarily released to permit the wheels to move freely during their rotation.

In the accompanying drawings, wherein like reference characters designate corresponding parts in the different views—

Fig. 1 is a top plan view, with certain parts removed, of the improved totalizer;

Fig. 2 is a front view of the totalizer, with parts removed, and showing its cooperation with the plate on the frame;

Fig. 3 is a general vertical cross sectional view through the totalizer and the frame of the machine, with parts omitted for clarity, taken at the right end of the totalizer shown in Fig. 2 with the casing thereof removed;

Fig. 4 is a somewhat diagrammatic partial view of certain parts removed from the machine and showing the parts in position when the numeral wheel is at zero position;

Fig. 5 is a partial perspective view of certain of the elements; and,

Fig. 6 is a similar view of certain other elements.

In the operation of this invention, which can be applied to any totalizer, it is preferably shown as applied to a cross totalizer, of a Remington

automatic total writing bookkeeper. In the drawings, the totalizer is provided with suitable frame plates 10 and 11 and a cover plate 12, beneath and between which the various operating parts are suitably housed and supported.

With special reference to Fig. 3, wherein some parts have been omitted for purposes of achieving clarity of understanding as to the operation of the invention, the side plates of the totalizer have been provided with the usual dovetail members 13 to permit it to be attached to the carriage if it is a vertical totalizer or to a truck (not shown) in a manner similar to that in which the totalizer 73 is attached to truck 74 as shown in Fig. 2 of the above mentioned Hart patent in which, as in the instant case, the said totalizer 13 is a cross totalizer and is not mounted directly on the carriage.

There is provided a series of number wheels 14 having pinions 15 fixed thereto and movable therewith. Each pinion is provided with a shortened tooth 16, and with teeth 17 of regular dimensions. A sensing element 18 is provided to contact with the pinion of each number wheel and is adapted to rest against the teeth of the pinion. Each sensing element 18 is pivoted at 19 and has an upward extension 20 pivotally connected by a link 21 to the lower arm 22 of a bell crank lever of which the other upstanding arm 23 thereof projects out of the casing of the totalizer as a finger. This bell crank is pivoted at 24. For each numeral wheel there is provided an independent combination of elements including the comb element 18, arm 20, link 21, and bell crank lever 22-23. When the wheel 14 is in a position representing a digit other than zero the regular teeth on it will cause the above lever system to assume the position shown in Fig. 3 in which case the fingers 23 will project substantially straight up.

As is illustrated in the U. S. patent to Roggenstein No. 2,412,537, issued December 10, 1946, when a cross totalizer is moved with the carriage past a predetermined position to write a total automatically, when the last digit other than zero in the total is presented to the sensing fingers an add-1 mechanism is operated to set up circuits or achieve certain desirable connections whereby the said last digit may be printed as a tens complement as is customary when the total being printed is a negative total. In accordance with one use to which the present invention may be applied, the totalizer shown herein is shown as a cross totalizer and the mechanism just above described may be used as an add-1 mechanism. In order to achieve this result, the fingers 23 when disposed in one position, preferably that in which they are placed by the presence in the totalizer of digits other than zero, are adapted to rub against the lower surface of a contact plate 25, during the movement of the fingers through a certain predetermined portion of the travel of the totalizer of which they are a part. The plate is of metal adapted to form part of an electric circuit and is resiliently supported by spring 26 (see Fig. 2) within a groove 27 in a supporting block 28. This block is insulatingly supported by means of insulating plates 29 in any suitable manner from a portion 30 of the fixed frame of the machine.

According to the disclosure in the Roggenstein patent above, when the last digit other than zero in a negative total is about to be printed an add-1 plate causes the add-1 (relay R-8) circuit to be broken and thus establish through the release of this relay a circuit which energizes the

tens complement relay R-5. In the instant invention the contact plate 25 is so disposed on the frame member 30 that when the finger 23, connected to the last digit wheel other than zero in a negative total, passes off the plate just before that figure is to be printed, the circuit of which the finger and the plate form a part is thus broken and a relay 31 corresponding to the relay R-3 in the above application is deenergized to close a contact 59 (R-5 of relay R-3 in the above application) whereby a tens complement circuit is made up as fully described in the above application. Only so much of the circuit is shown in Fig. 4 as is necessary to understand the present invention in connection with the tens complement circuit disclosed in the above application. It is of course obvious that the contact between the fingers 23 and the plate 25 can be used to control many other circuits and even be employed to achieve mechanical movements if desired.

When any number wheel 14 stands at zero its sensing element 18 will rest on the shortened tooth 16 thereof and this will permit the element 25 to move down further and thus operate the linkage to swing the finger connected thereto to a position shown in Fig. 4 wherein it will not contact with the plate 25 when the totalizer is moved past the plate 25. In Figs. 2 and 4 it is schematically clear that the totalizer, the fingers, the plate 25 and the relay 31 are part of a circuit which is closed whenever there is at least one finger in contact with the plate 25 but that this circuit is broken when the last upright finger passes beyond the plate to the position where the digit related to it is to be printed.

It will be understood, upon reference to Fig. 3, that the fingers 23 are in contact with the contact plate 25 to thereby establish the control circuit whereby the add-1 circuit is open when none of the numeral wheels are at their zero position. On the other hand, when all of the fingers 23 are out of contact with the plate 25, the control circuit is open to thereby close the add-1 circuit. In the mechanism as above described, the finger 23 of Fig. 3 is effective to close the control circuit and ineffective to close the add-1 circuit. Similarly, as seen in Fig. 4, the finger 23 is shown ineffective to close the control circuit, but effective to close the add-1 circuit.

When all the numeral wheels are set at zero and thus indicate that the totalizer is clear, the invention herein provides means settable under these conditions to permit a clear symbol to be printed. In Fig. 3 there is a universal bail element 32 pivotally supported by shaft 33 extending between the side plates 10 and 11 of the totalizer. This bail has spaced slots through which the rear portions of the links 21 extend. Each said link 21 has thereon a laterally projecting stud 34 disposed thereon in front of the bail 32 and when the link 21 is moved rearwardly the stud swings the bail counterclockwise. Each link is connected to one end of a spring 35 the other end of which is attached to some fixed member such as 36 in the machine and this spring tends to keep the link in a forward position and thus tends to press the sensing element 18 on the teeth of the pinion 15. As shown in Fig. 3 the element 18 is resting on one of the regular teeth of the numeral wheel pinion and consequently the link 21 is rearward and the finger 23 connected thereto is in the raised or upright position to contact the plate 25 when the totalizer moves past said plate. Since the bail 32 is contacted by the lugs

34 on all the links 21 it is obvious that as long as one link is in rearward position, indicating a numeral other than zero in at least one numeral wheel, the bail will be maintained in the position shown in this figure.

At its right end the bail is itself provided with a stud 37 which is adapted to bear against the upper end of an arm 38 of a bell crank lever pivoted at 39 the other arm 40 of which is forked at 41. This forked portion receives the end of an arm 42 rotatable on shaft 43 and forming part of a quadrant member 44 having teeth engaging teeth on a sensing disk or gear 45 rotatable on shaft 46 and having a sensing tooth 47. It is clear that when the upper end of arm 38 is pushed back by the stud on the bail 32 the tooth 47 will be moved in to one position, whereas when the bail is allowed to swing clockwise as the link 21 moves forwardly, a spring 48, fastened at one end to the arm 38 and at the other end to a fixed member 49 in the machine, will cause the movement of the tooth 47 to another position. Therefore it is to be noted that, when the sensing elements 18 are all resting on the low teeth of the pinions of the numeral wheels 14, the bail is allowed to move back to normal, the arm 38 is allowed to move forward, and the finger 47 is permitted to move to a position where it will engage a sensing finger (not shown) to print a clear symbol in a manner similar to the sensing of the teeth by sensing fingers in the above mentioned Roggenstein patent.

In order to permit free and unimpeded rotation of the numeral wheels when necessary such as during clearing or item entry, I have provided a novel means to achieve this result. This means is associated with a well known master dog such as 50 of the type shown clearly in the patents above mentioned. During item entry when the wheels have to be turned, this dog is operated by the actuator mechanism shown in these patents to lock the truck in position on which the totalizer is mounted and also operates a lever 51 the lower end of which engages the dog 50 when it is operated. This lever is pivoted at 39 and has an upper portion 52 provided with a rounded projection 53 adapted, when the lever is raised by the dog 50, to engage and swing a usual stop bail 54. This type of bail is shown in the patents supra, but in accordance with this invention is provided with an extra extension bail portion 55 having a dependent hook portion normally lying above and out of contact with rearwardly extending lips such as 57 on each sensing element arm 20. This bail 55 extends across the machine and is pivotally supported at 58. When the dog 50 is operated this bail is moved counter-clockwise as shown in Figure 3 and very slightly lifts the elements 18 from pressure contact with the teeth of the pinions 15 so that the wheels may be free to be turned whenever that is desired. Since the dogs are only operated temporarily the sensing elements are restored to normal position before the totalizer is allowed to move to the next position. This latter device is therefore means actuated during item entry or the rotation of the numeral wheels to free them momentarily from the retarding effect of the sensing element pressure.

While I have described what I consider to be highly desirable embodiments of my invention, it is obvious that many changes in form could be made without departing from the spirit of my invention, and I, therefore, do not limit myself to the exact form herein shown and described.

nor to anything less than the whole of my invention as hereinbefore set forth, and as hereinafter claimed.

What I claim as new and desire to secure by Letters Patent is:

- 5 1. In a machine of the class described, a normally open add-1 circuit, a totalizer having a plurality of numeral wheels, a sensing element respectively associated with each of said numeral wheels, means on the wheels to cause the movement of said sensing elements as the wheels move to and from a predetermined position, means including a movable finger associated with each of said sensing elements and adapted when effective to close said circuit, and means connecting each finger with its respective sensing element whereby the movement of the numeral wheels will move said fingers relatively to effective positions.
- 10 2. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 15 3. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 20 4. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 25 5. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 30 6. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 35 7. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 40 8. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 45 9. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 50 10. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 55 11. In a machine of the class described, a normally open add-1 circuit, a totalizer having a plurality of numeral wheels, a sensing element respectively associated with each of said numeral wheels, means including a movable finger associated with each of said sensing elements and adapted when effective to close said circuit, and means connecting each finger with its respective sensing element whereby the movement of the numeral wheels will move said fingers relatively to effective positions.
- 60 12. In a machine of the class described, having a normally open add-1 circuit, a totalizer having a plurality of numeral wheels, means including a finger projecting from the totalizer for each numeral wheel and adapted when in effective position relative to said add-1 circuit to close said add-1 circuit, connections between the wheels and their respective fingers, and means on the wheels and operatively associated with said connections to position the respective fingers in said effective position when the respective wheels are at zero position and to position the respective fingers in ineffective position relative to said add-1 circuit when the respective wheels are in any other position.
- 65 13. In a computing and printing machine hav-

ing, a frame, a to and fro travelling carriage, and a totalizer mounted on said carriage, the combination of an add-1 circuit, an add-1 relay, a contact plate, a control circuit connected through said contact plate for energizing and deenergizing said add-1 relay to open and close said add-1 circuit, a plurality of numeral wheels, a plurality of sensing elements respectively associated with the wheels, means on the wheels to cause the movement of said sensing elements as the wheels move to and from a predetermined position, a plurality of fingers projecting from the totalizer, means connecting each finger with a sensing element whereby the movement of the sensing elements will move the fingers from effective to ineffective positions, said fingers adapted to contact with said plate to close said control circuit when disposed in their effective positions relative to said control circuit and to be out of contact to open said circuit when disposed in their ineffective position relative to said control circuit whereby said add-1 circuit is opened and closed respectively.

7. In a computing and printing machine having a frame, a to-and-fro travelling carriage, a contact plate mounted on said frame and a totalizer mounted on said carriage, the combination of an add-1 circuit, a control circuit connected through said contact plate for opening and closing said add-1 circuit, a plurality of numeral wheels on said totalizer, a plurality of fingers projecting from said totalizer, means under control of said wheels and connected to the respective fingers to move the fingers from one position to another as the respective wheels move to and from a predetermined position, the fingers of the totalizer adapted to contact with said contact plate to close said control circuit when disposed in one position and to be out of contact therewith to open said control circuit when in another position whereby said add-1 circuit is opened and closed respectively.

8. In a computing and printing machine having a frame, a to-and-fro travelling carriage, a contact plate mounted on said frame and a totalizer mounted on said carriage, the combination of an add-1 circuit, a control circuit connected through said contact plate for opening and closing the add-1 circuit, a plurality of numeral wheels on said totalizer, a plurality of fingers projecting from said totalizer, means under control of said wheels and connected to the respective fingers to move the fingers from effective to ineffective position as the respective wheels move to and from their zero position thereof, the fingers of the totalizer adapted to contact with said contact plate to close said control circuit when disposed in one position and to be out of contact therewith to open said control circuit when in another position as the totalizer is moved past said plate.

9. In a computing and printing machine having a frame, a to-and-fro travelling carriage, a contact plate mounted on said frame and a totalizer mounted on said carriage, the combination of an add-1 circuit, a control circuit connected through said contact plate for opening and closing the add-1 circuit, a plurality of numeral wheels on said totalizer, a plurality of sensing elements respectively associated with the wheels, means on the wheels to cause the movement of the sensing element of each wheel as it moves to and from the zero position thereof, a plurality of fingers projecting from the totalizer, means connecting each finger with a sensing ele-

ment whereby the movement of the sensing element will move the respective finger from one position to another, the fingers of the totalizer adapted to contact with said contact plate to close said control circuit when disposed in one position and to be out of contact therewith to open the control circuit when in another position as the totalizer is moved past said plate.

10. In a computing and printing machine having a frame, a to-and-fro travelling carriage, a contact plate mounted on said frame and a totalizer mounted on said carriage, the combination of an add-1 circuit, a control circuit connected through said contact plate for opening and closing said add-1 circuit, a finger projecting from the totalizer for each numeral wheel, connections between the wheels and their respective fingers, means on the wheels and operatively associated with said connections to position the respective fingers in one position when the respective wheels are at zero position and to position the respective fingers in another position when the respective wheels are in any other position, the fingers of the totalizer adapted to contact with said contact plate to close said control circuit when disposed in said one position and to be out of contact therewith and to open said circuit when in said other position as the totalizer is moved past said plate.

11. In a computing and printing machine having a frame, a to and fro travelling carriage, a contact plate mounted on said frame and a totalizer mounted on said carriage, the combination of an add-1 circuit, a control circuit connected through said contact plate for opening and closing said add-1 circuit, a plurality of numeral wheels, a plurality of sensing elements respectively associated with said wheels, means on the wheels to cause the movement of the sensing element of each as the wheels move to and from a predetermined position, a plurality of movable fingers projecting from the totalizer and adapted when in effective position relative to said control circuit to close said control circuit, means connecting each finger with a sensing element whereby the movement of the sensing elements will move the fingers from effective to ineffective positions, a clear signal control device movable to operative and inoperative positions, and means associated with said clear signal control device and under control of said connecting means to hold the control device in inoperative position whenever any one or more numeral wheels is in any position except the zero position.

12. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of movable fingers projecting from the totalizer and adapted when in effective position relative to said control circuit to close said control circuit, means associated with the wheels and connected to the respective fingers to move the fingers from ineffective to effective position as the respective wheels move to and from a predetermined position, a clear signal control device movable to operative and inoperative positions, and means associated with said clear signal control device and under control of said connecting means to hold the clear signal control device in inoperative position whenever any one or more numeral wheels is in any position except the zero position.

13. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of movable fingers projecting from the totalizer and adapted when in effective position relative to said control circuit to close said control circuit, means associated with the wheels and connected to the respective fingers to move the fingers from effective to ineffective position and vice versa as the respective wheels move to and from their zero position, a clear signal control device movable to operative and inoperative positions, and means associated with said clear signal control device and under control of said connecting means to hold the clear signal control device in inoperative position whenever any one or more numeral wheels is in any position except the zero position.

14. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of movable fingers projecting from the totalizer and adapted when in effective position relative to said control circuit to close said control circuit, a plurality of numeral wheels on said totalizer, a plurality of sensing elements respectively associated with said wheels, means on the wheels to cause the movement of the sensing element of each as the wheels move to and from their zero position, means connecting each finger with a sensing element whereby the movement of the sensing elements will move the fingers from one position to another, a clear signal control device movable to operative and inoperative positions, and means associated with said clear signal device and under control of said connecting means to hold the control device in inoperative position whenever any one or more numeral wheels is in any position except the zero position.

15. In a machine of the class described, an add-1 circuit, a control circuit for opening and closing said add-1 circuit, a totalizer having a plurality of numeral wheels, means including a finger projecting from the totalizer for each numeral wheel and adapted when in effective position relative to said control circuit to close said control circuit, connections between the wheels and their respective fingers, and means on the wheels and operatively associated with said connections to position the respective fingers in their ineffective position when the respective wheels are at zero position and to position the respective fingers in their effective position when the respective wheels are in any other position, a clear signal control device movable to operative and inoperative positions, and means associated with said clear signal control device and under control of said connecting means to hold the clear signal control device in inoperative position whenever any one or more numeral wheels is in any position except the zero position.

16. In a machine of the class described, an add-1 circuit, a control circuit for opening and closing said add-1 circuit, a totalizer having a plurality of numeral wheels, a plurality of sensing elements respectively associated with said wheels, means on the wheels to cause the movement of the element of each as the wheels move

to and from a predetermined position, a plurality of fingers projecting from the totalizer and adapted when in effective position relative to said control circuit to close said control circuit, means connecting each finger with a sensing element whereby the movement of the sensing elements will move the fingers from effective to ineffective position, a clear signal device control movable to operative and inoperative positions, and means associated with said clear signal control device and under control of said connecting means to hold the clear signal control device in inoperative position whenever any one or more numeral wheels is in any position except the zero position.

17. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of numeral wheels on said totalizer, a plurality of fingers projecting from said totalizer, means associated with the wheels and connected to the respective fingers to move the fingers from ineffective to effective position as the respective wheels move to and from a predetermined position, said fingers adapted to contact with the plate and close the control circuit when disposed in one position and to be out of contact therewith and to open said control circuit when in another position as the totalizer is moved past said plate, a clear signal control device movable to operative and inoperative positions and means associated with said clear signal control device and under control of said connecting means to hold the clear signal control device in inoperative position whenever any one or more numeral wheels is in any position except the zero position.

18. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of numeral wheels on said totalizer, a plurality of fingers projecting from said totalizer, means associated with the wheels and connected to the respective fingers to move the fingers from effective to ineffective position as the respective wheels move to and from their zero position thereof, said fingers adapted to contact with the plate and close the control circuit when disposed in one position and to be out of contact therewith and to open said control circuit when in another position as the totalizer is moved past said plate, a clear signal control device movable to operative and inoperative positions, and means associated with said clear signal control device and under control of said connecting means to hold the clear signal control device in inoperative position whenever any one or more numeral wheels is in any position except the zero position.

19. In a computing and printing machine having a frame, a to and fro travelling carriage, a contact plate mounted on said frame and a totalizer mounted on said carriage, the combination of an add-1 circuit, a control circuit connected through said contact plate for opening and closing the add-1 circuit, a plurality of numeral wheels on said totalizer, a plurality of sensing elements respectively associated with said wheels, means on the wheels to cause the movement of the sensing element of each wheel as

it moves to and from the zero position thereof, a plurality of fingers projecting from the totalizer, means connecting each finger with a sensing element whereby the movement of the sensing element will move the respective fingers from one position to another, said fingers adapted to contact with the plate to close said control circuit when disposed in one position and to be out of contact therewith and to open said control circuit when in another position as the totalizer is moved past said plate, a clear signal control device movable to operative and inoperative positions, and means associated with said clear signal control device and under control of said connecting means to hold the clear signal control device in inoperative position whenever any one or more numeral wheels is in any position except the zero position.

20. In a computing and printing machine having a frame, a to and fro travelling carriage, a contact plate mounted on said plate and a totalizer mounted on said carriage, the combination of an add-1 circuit, a control circuit connected through said contact plate for opening and closing the add-1 circuit, a plurality of numeral wheels on said totalizer, a finger projecting from the totalizer for each numeral wheel, connections between the wheels and their respective fingers, and means on the wheels and operatively associated with said connections to position the respective fingers in their ineffective position relative to said control circuit when the respective wheels are at zero position and to position the respective fingers in effective position relative to said control circuit when the respective wheels are in any other position, said fingers adapted to contact with the plate to close said control circuit when disposed in said effective position and to be out of contact therewith and to open said control circuit when in said ineffective position,

5 a clear signal control device movable to operative and inoperative positions, and means associated with said clear signal control device and under control of said connecting means to hold the clear signal control device in inoperative position whenever any one or more numeral wheels is in any position except the zero position.

25 21. In a totalizer having a plurality of numeral wheels with a pinion movable with each wheel, one of the teeth of each pinion being shortened, sensing elements adapted to press against the teeth of the pinions, a link connected to each sensing element, a movable finger connected to each of said links, said finger projecting outwardly from the totalizer, studs on each link, a bail member having a normal position and adapted to be engaged and moved by any one of said studs when any one of said links are moved, a clear signal control device movable to operative and inoperative positions, and means associated with said clear signal control device and under control of said connecting means to hold the clear signal control device in inoperative position whenever any one or more numeral wheels is in any position except the zero position.

EMIL F. THIERFELDER.
